SINGLE LEVER ENGINE CONTROL

John F. Morse, Hudson, and Donald W. Waner, Munroe Falls, Ohio, assignors to The Morse Instrument Company, Hudson, Ohio, a corporation of Ohio

Application October 4, 1957, Serial No. 688,183

2 Claims. (Cl. 192—.096)

The invention relates generally to a control unit having a single lever for controlling the clutch and throttle of an internal combustion engine, or other mechanism requiring sequencing controls. More particularly, the invention relates to a single lever control unit for normally operating the clutch and throttle in unison but adapted selectively to operate the throttle alone.

The primary object of the present invention is to provide an adjustment for selectively disconnecting the clutch operating shaft from the throttle operating shaft so that the throttle can be operated through its full range with the clutch disengaged.

A further object is to provide for connection or disconnection of the clutch operating shaft with respect to the throttle operating shaft only while the clutch is held disengaged from the forward and reverse gear of the engine.

The control unit of the present invention is particularly adapted for the control of outboard marine engines, but may also be used for other engines operated by a reverse gear and throttle, as well as other devices operated by sequencing controls. The unit is compact and inexpensive to make, and is designed for proper and safe operation by anyone following their natural reactions.

The improved control unit has rotatable shafts mounted in parallelism and adapted for operative connection with the throttle and clutch of an engine, said shafts being connected within the unit whereby the clutch control shaft is rotated during only part of the rotation of the throttle control shaft, and the clutch control shaft being disconnectable from the throttle control shaft only when the shafts are in neutral position.

The objects of the invention are accomplished by the improvements comprising the present invention, preferred embodiments of which are shown by way of example in the accompanying drawings and described in detail herein. Various modifications and changes in details of construction may be made without departing from the scope of the invention as defined in the appended claims.

Referring to the drawings:

Fig. 1 is a vertical sectional view of one embodiment of the improved single lever control unit, showing the control lever in neutral or non-operating position.

Fig. 2 is a rear elevation thereof.

Fig. 3 is a sectional view at right angles to Fig. 1, as on line 3—3 of Fig. 1.

Fig. 4 is a similar view showing the control lever in full lines in its 45° position where the clutch is fully engaged and further movement of the lever continues to advance the throttle without disturbing the clutch.

Fig. 5 is a sectional view similar to Fig. 3 of a modified embodiment of the invention, with the control shafts in neutral position.

Fig. 6 is a similar view with the control shafts in the positions of Fig. 4.

2

Referring to the embodiment of Figs. 1—4, the unit preferably comprises a housing having a front plate 10 and a rear plate 11. The plates are clamped together in abutment by bolts 12 passing through registering countersunk holes in both plates. As shown, the inner abutting portion of the front plate 10 may have a laterally extending flange 13 around its periphery for mounting the unit on a suitable support by means of bolts or screws 14.

The front plate 10 preferably has upper and lower journal bosses 15 and 16 formed therein, and the rear plate 11 has upper and lower journal bosses 17 and 18 registering with the journal bosses 15 and 16, respectively. A throttle operating shaft 19 is journaled in the upper bosses 15 and 17 and a clutch operating shaft 20 is journaled in the lower bosses 16 and 18.

The shafts 19 and 20 are operatively connected to each other by suitable means such as the mutilated gears shown in Figs. 1—4, so that rotation of the shaft 19 in either direction will rotate shaft 20 in the opposite direction during only an initial portion of the rotation of shaft 19, and the shaft 20 is held in a predetermined rotated position during further rotation of shaft 19 in the same direction as its initial rotation. Another mechanism which may be used to obtain substantially the same result is a Geneva mechanism such as shown in Figs. 5 and 6. Other well-known mechanisms may be used, if desired, to obtain similar results.

In the embodiment of Figs. 1 to 4, a mutilated or interrupted gear 21 is fixed on shaft 19 as by a pin 22 between the journal bosses 15 and 17, and has a toothed segment 23 on its lower portion. A mutilated or interrupted gear 24 is mounted on shaft 20 between the journal bosses 16 and 18, and has an upper toothed segment 25 for meshing with segment 23. Preferably, the gear segments have the same pitch diameter, and the peripheral length of the segments is designed so that gear 24 will be rotated in the opposite direction from gear 21 during 90° of rotation of gear 21.

The neutral position of the gears is shown in Fig. 3, and rotation of gear 21 from neutral position 45° in either direction will rotate gear 24 45° in the opposite direction, as shown in Fig. 4. A throttle operating lever arm 26 is attached to the rear end of shaft 19 and a clutch operating lever arm 27 is attached to the rear end of shaft 20. The relative positions of these operating arms at neutral and at 45° rotation in one direction is shown in chain lines in Figs. 3 and 4. In the neutral position of the gears the throttle is set at idling speed and the clutch is fully disengaged.

The single operating lever 28 for the unit is fixed on the front end of throttle shaft at the face of the front plate 10. Preferably, the lever 28 has a split socket portion 30 clamped on the shaft 19 by a set screw 31. The lever 28 is preferably clamped on the shaft 19 so as to be in a vertical upright position in the neutral position of the shafts, as best shown in Fig. 3.

The gear 24 is journaled on shaft 20, and means is provided for selectively keying the gear to the shaft so that rotation of the gear 24 by gear 21 will either rotate the clutch control shaft 20 or allow the gear to idle on the shaft, as desired. This means comprises providing a pin 32 extending diametrically through the shaft with its ends projecting radially therefrom, and slots in the gear 24 and the journal boss 16 for receiving the pin selectively as the shaft is moved axially of the gear. Preferably, a knob 33 is formed on the front end of shaft 20 to facilitate grasping the shaft to move it axially, and a spring-biased ball detent 34 is provided in boss 18 to frictionally engage one or the other of two annular grooves 35 and 36.

When the detent 34 engages groove 35, as shown in full lines in Fig. 1, the pin 32 is engaged in a slot 37 in gear 24, and when detent 34 engages groove 36 the pin 32 is engaged in a slot 38 in journal boss 16, as shown in chain lines in Fig. 1. In this embodiment, the slot 38 is vertically disposed and the slot 37 is arranged to be in vertical position when the gears are in neutral position. Hence the only time the slots 37 and 38 are in register to permit axially shifting the shaft 20 is in the neutral position of the gears, at which time the throttle is at 10 idling speed and the clutch disengaged.

A spring-biased ball detent 40 is mounted in the upper portion of flange 13 of the housing for frictionally engaging the upper periphery of gear 21, and a groove 41 is provided in the gear to frictionally retain the gear 21 and shaft 19 in the neutral position. Similar notches or grooves 42 may be provided on opposite sides of groove 41 at 45° therefrom to indicate to the operator by feel the positions at which the clutch is fully engaged.

The lever arms 26 and 27 are operatively connected with the throttle and clutch of the engine by any suitable and well-known means, such as flexible push-pull cables, push rods, etc. As indicated in Fig. 2, when the control unit is in neutral position with the control lever vertical, the throttle control arm 26 is horizontal and the clutch control arm 27 is vertical and depending downwardly from shaft 20 and at 90° to arm 26. The arm 26 may be connected at 46 by a push rod (not shown) to a throttle operating lever at a point A₁ in horizontal alignment with the arm.

As the control lever is rotated clockwise, as seen in Fig. 2, to the 45° position shown in chain lines, it will be seen that the point A₁ moves only a slight amount to the position A₂ because the initial movement is substantially along the tangent to the arc of movement of arm 26. Thus, allowing for the usual amount of backlash in the cable system, the throttle setting is advanced only a slight amount during the first 45° of movement of the arm 26, and as seen in Fig. 4 this 45° of movement moves the clutch lever 27 45° in the opposite direction to fully 40 engage the clutch. If desired, suitable means for controlling the amount of backlash may be provided.

As the lever 28 is moved clockwise beyond the 45° point, the gear segment 25 is disengaged from gear segment 23 so that arm 27 remains at the 45° position of Fig. 4. However, the arcuate face 47 of gear 24 rotatively engages the cylindrical surface of gear 21 as gear 21 continues to rotate so that arm 27 is maintained in the 45° position with the clutch engaged. As the lever arm 26 is rotated from the 45° position to the vertical 90° position, the point A₁ moves a substantial distance to position A₃ which advances the throttle to full open position with the clutch engaged. Reverse rotation of the control lever 90° from neutral will engage the clutch and drive the engine in the opposite direction.

In the embodiment of Figs. 5 and 6 the housing is substantially the same construction as the housing in Figs. 1-4, and includes a front plate 110 having a laterally extending flange 113. The throttle control and clutch control shafts 119 and 120 are shown somewhat smaller in diameter, and have the throttle and clutch operating levers 26 and 27 attached to their rear ends in the same relative positions as in Figs. 3 and 4. The operating lever 28 is attached to the front end of the throttle control shaft 119 and is vertically upright in the neutral position of the shafts.

In this embodiment the shafts are operatively connected to each other by a Geneva mechanism comprising intermeshing drive elements or cams 121 and 124 on the shafts 119 and 120, respectively. The cam 121 has a transversely slotted projection 143 with a pin 144 at its outer end which, in the neutral position, is located at the bottom of a radial slot 148 formed in a projection 149 on the cam 124. The projection 149 extends into the transversely slotted projection 143, as shown. The cam 121 is fixed on shaft

5

119 by a pin 122, and the cam 124 is selectively keyed to shaft 120 by a pin 132. The pin 132 is horizontal in the neutral position of the shafts, and is movable with axial movement of the shaft 120 selectively into a horizontal slot 137 in cam member or an aligned horizontal slot 138 in the housing. Axial movement of shaft 120 is possible only when the shafts are in neutral with the slots 137 and 138 in register.

As the control lever 128 is rotated clockwise from the neutral position of Fig. 5 to the 45° position shown in full lines in Fig. 6, the throttle control shaft 119 is rotated 45° clockwise and the shaft 120 is rotated 45° counter-clockwise by the sliding engagement of pin 144 in slot 148. Further rotation of shaft 119 in a clockwise direction causes pin 144 to leave slot 148, and the shaft 120 remains stationary as the shaft 119 is rotated to the 90° position shown in chain lines. During said further rotation the concave surface 150 of projection 149 rotatively engages the convex cylindrical surface of cam 121, so that clutch control shaft and arm 27 is maintained in the 45° position with the clutch engaged, as the throttle arm 26 is fully advanced to the 90° position.

It will be seen that by shifting the shaft 20 or 120 axially when the control lever 28 is in neutral position, the clutch control gear 24 or cam 124 may be engaged with or disengaged from driving connection with said shaft. Thus, the engine may be run from idling speed to full throttle without engaging the clutch, when it is desired to check the engine speed at higher r.p.m. than at neutral, or for starting the engine, or in order to run auxiliary equipment, or for any other reason.

However, as a safety feature, the clutch operating gear can only be disconnected at neutral position, and once it is disconnected it can not be reconnected without returning the throttle to neutral position.

The normal operation of the improved unit is simple and foolproof because a single lever controls the whole operation. If the unit is used to control the operation of a marine engine, pushing the lever forward moves the boat forward and pushing it reversely moves the boat backward. Thus a person's natural reactions, even if excited or confused, result in making the right move in the right amount at the right time. There is no chance of mistaking the clutch lever for the throttle lever or vice versa. Moreover, the reverse gear of the engine is protected from damage because the throttle is automatically closed when the clutch is disengaged.

What is claimed is:

1. A control unit for the clutch and throttle of an engine, comprising a housing, a throttle control shaft and a clutch control shaft journaled in said housing, a control lever fixed on said throttle control shaft, a drive element secured on said throttle control shaft, a drive element journaled on said clutch control shaft, said elements having meshing portions to operate said clutch control shaft only during part of the rotation of the throttle control shaft in either direction from a neutral position, a drive pin in said clutch control shaft and slots in the element thereon and in the housing for receiving said pin when the shaft is moved axially, and said slots being in register only when the shafts are in neutral position.

2. A control unit for the clutch and throttle of an engine, comprising a housing, a throttle control shaft and a clutch control shaft journaled in said housing, a control lever fixed on said throttle control shaft, a drive element secured on said throttle control shaft, a drive element journaled on said clutch control shaft, said elements having meshing portions to operate said clutch control shaft only during part of the rotation of the throttle control shaft in either direction from a neutral position, a drive pin in said clutch control shaft and slots in the element thereon and in the housing for receiving said pin when the shaft is moved axially, said slots being in register only when the shafts are in

neutral position, and means operatively connecting the throttle control shaft to the engine throttle for advancing the throttle a slight amount during said part rotation of the throttle control shaft in either direction from a neutral position and for advancing the throttle 5 a substantial amount during further rotation of the throttle shaft to full open position.
